UNITED STATES PATENT OFFICE.

JOSEPH E. ROYCE, OF PUEBLO, COLORADO.

DRILL-BRACKET.

1,068,170.

Specification of Letters Patent.

Patented July 22, 1913.

Application filed May 8, 1912. Serial No. 696,041.

To all whom it may concern:

Be it known that I, JOSEPH E. ROYCE, citizen of the United States, residing at Pueblo, in the county of Pueblo and State of Colorado, have invented certain new and useful Improvements in Drill-Brackets, of which the following is a specification.

My invention relates to drill brackets for supporting drills in proper position during their operation, and the object of my invention is to provide a bracket which will hold the upper or free end of the drill against all wobbling due to uneven movement of the drill-driving mechanism.

15. A further object of my invention is to provide a drill bracket which may be readily adjusted to hold a drill at various lengths and to hold the same at all angles, thus adapting the bracket for use with a wide range of work.

A still further object of my invention is to improve the construction and increase the efficiency of the brackets of the above-described character.

25. With these and other objects in view, my invention will be more fully described, illustrated in the accompanying drawing, and then specifically pointed out in the claim which is attached to and forms a part of this application.

In the drawing:—Figure 1 is a perspective view of my improved drill bracket; Fig. 2 is a side elevation showing the bracket in use, parts being shown in section to more clearly bring out the construction.

Corresponding and like parts are referred to in the following description and indicated in all the views of the accompanying drawing by the same reference characters.

The preferred embodiment of my bracket consists primarily of a base 10, a standard 11 secured at one end to one end of the base, and a drill-engaging member 12 mounted 45 upon the standard and adjustable longitudinally thereon and at various angles thereto.

Referring more particularly to the parts, all of which are made of metal, preferably cast malleable iron, the base consists of a 50 substantially rectangular piece of metal having a longitudinally extending slot 13 and terminating at one end in a vertically disposed, circular head 14 which as shown, is disposed at one side of the longitudinal center of the base and is provided with a centrally positioned, laterally extended stud

15. The inner face of this head is also provided with a plurality of radially extending teeth 16.

The standard 11 includes a cylindrical body member terminating at one end in a circular head 17 provided with a centrally located bore and upon one face with a plurality of radially extending teeth adapted to engage with the teeth 16 of the head of the base when the parts are in assembled position. The stud 15 is threaded to receive a nut 18, by means of which the base and standard may be clamped in adjusted position, the interlocking teeth formed upon the opposed faces of the heads preventing all shifting of the base and standard when the nut is tightened.

Slidably mounted upon the standard is a split sleeve 19, the free edges of which are extended laterally to form clamping ears 20 which are bored to receive a bolt 21 having a clamping nut 22, by means of which the sleeve may be secured in adjusted position upon the standard. The sleeve is provided at a point, substantially opposite the head, with an extension 23 which is provided with a bolt-receiving bore 24 and with radially extending teeth 25 directed from the bore.

85 The drill-engaging member comprising a body having its upper face beveled at one end, as shown at 26, and formed at its other end with a circular head 27 having a laterally directed stud 28 formed upon its inner face and a plurality of locking teeth extending radially from the stud. This stud 28 passes through the bore 24 and is threaded to receive a nut 29, by means of which the drill-engaging member may be clamped in adjusted position.

80 As shown, the extension 23 is somewhat offset in the axial center of the sleeve, and the head 27 of the drill-engaging member is similarly offset from the longitudinal center of said member, this construction bringing the drill-engaging member into the same plane with the standards. The lower face of the drill-engaging member is preferably provided with a plurality of spaced apart, shallow recesses adapted to engage the upper end of the drill and hold the same from slipping.

100 In operation, the base of the tool may be placed upon any suitable support and, if necessary, clamped thereto by bolts passed through its slot. The standard is then ad-

justed with respect to its base in such a manner as to extend in parallel relation to the bit or drill being employed, and the sleeve 19 is adjusted upon the standard in 5 such a manner that the drill-engaging member will bear upon the upper end of the drill when extended at right angles to the standard. This engagement of the free end of the drill by the member 12 absolutely 10 prevents all movement of the drill other than the desired rotary movement, and as the drill is advanced the sleeve may be lowered upon the standard to constantly maintain the drill-engaging member in operative 15 position.

From the foregoing description, it will be apparent that I have provided a simple and efficient form of drill bracket, and one which because of its many adjustments is 20 adapted for a wide range of work.

Having thus described my invention, what I claim is:—

A drill bracket comprising a base plate slotted longitudinally and disposed to be 25 adjustably mounted upon a supporting member, said base member being reduced in width adjacent one of its terminals and provided with a circular head disposed at right

angles to its body portion, one face of said head being formed with radially disposed 30 teeth, a cylindrical standard the lower terminal of which is formed with a head, said head being provided with radial teeth disposed to engage in the throats of the teeth in the head of the base, a binding screw arranged to hold them in contact, a clamp mounted on the standard, said clamp being capable of longitudinal and rotary movement on the standard, means for locking the clamp against movement on the standard, 40 the clamp comprising members one of which is more extensive than the other, the more extensive member being formed with teeth, a flat drill engaging bar formed with a head having teeth disposed to engage the 45 toothed portion of the more extensive member of the clamp, said drill engaging member having a tapered terminal, the under face of the member being flat and provided with stock receiving depressions. 50

In testimony whereof I affix my signature in presence of two witnesses.

JOSEPH E. ROYCE. [L. S.]
